[57] CLAIM

The ornamental design for a pedestal for a CRT housing, as shown and described.

DESCRIPTION

FIG. 1 is a right top front perspective view of the pedestal for a CRT housing showing my new design;

FIG. 2 is a front elevational view thereof;

FIG. 3 is a back elevational view thereof;

FIG. 4 is a top plan view thereof;

FIG. 5 is a bottom plan view thereof;

FIG. 6 is a right side elevational view thereof;

FIG. 7 is a left side elevational view thereof.

The display monitor is shown in broken lines in FIGS. 2-7 for illustrative purposes only.

FIG. 1

FIG. 2

FIG. 3

FIG. 4

FIG. 5

FIG. 6

FIG. 7
